COMBINATION DIGGING AND CARRYING SCRAPER

Stewart F. Armington, Willoughby, Ohio, and
William J. Adams, Santa Cruz, Calif., assignors
to The Euclid Road Machinery Co., Euclid,
Ohio, a corporation of Ohio

Application December 27, 1949, Serial No. 6,852

Term of patent 14 years

(Cl. D14—3)

To all whom it may concern:

Be it known that we, Stewart F. Armington and William J. Adams, citizens of the United States, residing respectively at Willoughby, State of Ohio, and Santa Cruz, State of California, have invented a new, original, and ornamental Design for a Combination Digging and Carrying Scraper, of which the following is a specification, reference being had to the accompanying drawing, forming a part hereof.

In said drawing,

Fig. 1 is a left-hand side elevational view of a combination digging and carrying scraper, showing our design, the right-hand side being the same;

Fig. 2 is a front elevational view of the same;
Fig. 3 is a rear elevational view of the same;
Fig. 4 is a side perspective view thereof.

We claim:

The ornamental design for a combination digging and carrying scraper, as shown and described.

STEWART F. ARMINGTON.
WILLIAM J. ADAMS.
